s.c.(57) CLAIM

The ornamental design for a holder for a golf ball marker, as shown and described.

DESCRIPTION

FIG. 1 is a top view of a holder for a golf ball marker showing our new design;

FIG. 2 is a bottom view thereof;

FIG. 3 is a perspective view thereof;

FIG. 4 is a front view thereof;

FIG. 5 is a rear view thereof;

FIG. 6 is a right side thereof, the opposite side being a mirror image;

FIG. 7 is another perspective view thereof; and,

FIG. 8 is a perspective view of the holder for a golf ball marker. The broken line showing the golf ball marker forms no part of the design.
